UNITED STATES PATENT OFFICE.

LEO MORSE, OF NEW YORK, N. Y.

VANITY-BOX.

1,077,093.

Specification of Letters Patent. Patented Oct. 28, 1913.

Application filed May 27, 1913. Serial No. 770,142.

To all whom it may concern:

Be it known that I, LEO MORSE, a citizen of the United States, and a resident of the city of New York, borough of Manhattan, 5 in the county and State of New York, have invented a new and Improved Vanity-Box, of which the following is a full, clear, and exact description.

This invention relates to novelty toilet articles and has particular reference to what 10 are commonly called vanity boxes.

Among the objects of the invention is to provide a box of novel and attractive form and construction having special adaptation 15 for being carried in a hand bag or the like or for use upon a dresser.

A further object of the invention is to provide a holder or receptacle for a powder puff whereby the same is carried and kept 20 in a proper form for use.

The foregoing and other objects of the invention will hereinafter be more fully described and claimed and illustrated in the drawings forming a part of this specification 25 in which like characters of reference indicate corresponding parts in all the views, and in which—

Figure 1 is a perspective view of a preferred form of vanity box made in accordance with this invention; Fig. 2 is a similar view of the main portion or compartment thereof; and Fig. 3 is a transverse section through the entire construction on the line 3—3 of Fig. 1.

The box proper comprises a base 10 and an upwardly extending shell 11, the form of which in cross section is substantially semi-cylindrical whereby several advantages are obtained. A box in this form is most convenient for carrying in one's pocket or a bag, and as shown in Fig. 2 it is very convenient for the reception of a powder puff having the form and nature illustrated. The box is provided with a cover or lid 12 having a top 13 corresponding substantially in size and form to the bottom member 10. The flat side 12' of the cover is shown provided with a mirror 14 secured thereon permanently by means of a rim 15. The box, 45 including its cover and said rim 15, are all made preferably of celluloid or some other suitably strong and durable material.

At 16 I show what may be considered as a fountain powder puff, the same compris-

ing a hemispherical bag 17 of substantially 55 loose fibrous material and provided with a rim 18 of metal or other rigid material surrounding the mouth thereof which forms a base also for a coil spring 19 within the bag. A cap 20 is fitted in said mouth where it is 60 retained by friction in connection with said rim 18. Said cap is provided with a finger piece comprising a ring 21 connected to the cap by means of a shank 22 whereby the powder puff may be manipulated while in 65 use and by which the cap may be removed for the purpose of replenishing the powder puff with powder. The vertical wall 11 of the main portion of the box is provided with an open-ended slot 23 through which 70 the shank 22 projects when the powder puff is slipped into place. The ring 21 is adapted to lie flatly against the outer face of said wall, and by reason of the form and flexibility of the adjacent parts of the box, the 75 lid will slip thereover readily and make a complete closure with a very neat appearance. The spring 19 maintains the puff in proper form and assists in causing the delivery of the powder through the fibrous 80 material 17. A finishing material in the nature of a ribbon or the like is indicated at 24 and provides a neat trimming for the powder puff, the same being inserted between the outer edge of the rim 18 and the 85 adjacent portion of the fibrous material 17. The outer edge or rim 20' of the cap is adapted to bear against said trimming.

Having thus described my invention, I claim as new and desire to secure by Letters Patent:—

1. In a vanity box, the combination of a box proper having a bottom and upwardly projecting walls, one of said walls having an open-ended slot, a powder puff fitted and 95 carried within said box including a shank projecting through said slot and a handle pivoted to the outer end of said shank adapted to lie against the outer surface of the slotted wall, and a cover for the box 100 extending over said shank and handle.

2. In a vanity box, the combination of a box proper of substantially semi-cylindrical form including one flat wall having an open-ended slot at its upper portion, a substantially hemispherical powder puff carried within said box proper, said powder puff having a shank and a ring pivoted to the 105

outer end of the shank, said shank being adapted to project through said slot with the ring engaging the outer surface of the flat wall of the box proper, and a slideable cover for the box surrounding the powder puff and having a flat wall lying against the shank and ring aforesaid.

In testimony whereof I have signed my name to this specification in the presence of two subscribing witnesses.

LEO MORSE.
